DESIGN FOR A TABLE LAMP

Dorothy G. Helmer, Indianapolis, Ind., assignor to Electrical Testing Laboratories, New York,
N. Y., a corporation of New York

Application August 11, 1938, Serial No. 79,246

Term of patent 3½ years

To all whom it may concern.

Be it known that I, Dorothy G. Helmer, a citizen of the United States of America and a resident of Indianapolis, in the county of Marion and State of Indiana, have invented a new, original, and ornamental Design for a Table Lamp, of which the following is a specification, reference being had to the accompanying drawing, forming a part thereof.

The figure is a side elevation of the entire lamp, showing my new design.

I claim:

The ornamental design for a table lamp, as shown.

DOROTHY G. HELMER.
